UNITED STATES PATENT OFFICE

MARTIN E. CARTER, OF LA ROMANA, DOMINICAN REPUBLIC

JUICE STRAINER

Application filed October 26, 1929. Serial No. 402,746.

This invention relates to liquid strainers and more particularly to an apparatus especially adapted for use in straining cane juices for use in sugar making with a view to separating therefrom trash or cane fibre contained in the liquid as removed from the crushing rolls.

An important object of the invention is the improvement of an apparatus disclosed in my prior United States Patent, No. 1,594,999 granted August 3, 1926, for juice strainer, to increase the efficiency thereof in the straining operation.

A further and more specific object of the invention is the provision of a construction preventing splashing of dirty liquid into the liquid which has been treated by the screening apparatus.

A further object of the invention is the provision of an improved inlet for such screening devices whereby the incoming liquid is more evenly distributed along the screen and piling up of the liquid at one end thereof avoided.

A still further object of the invention is the provision of an inlet or supply pipe having auxiliary supply pipes associated therewith and disposed within the screening apparatus which are so arranged that the extent to which the liquid is distributed over the surface of the screen is increased.

A still further object of the invention is to provide a construction permitting the use of a closed tank for the screening apparatus.

A further object of the invention is the provision of an improved screen structure both in the general make-up thereof and in the manner of mounting the same upon the supporting end castings.

These and other objects I attain by the construction shown in the accompanying drawings wherein, for the purpose of illustration, I have shown a preferred embodiment of my invention and wherein:

Fig. 1 is a side elevation taken on the line 1—1 of Fig. 2;

Fig. 2 is a transverse sectional view through the juice straining apparatus;

Fig. 3 is an end view showing driving mechanism;

Fig. 4 is a view of one of the screen segments; and

Fig. 5 is an enlarged fragmentary view of the screen in section showing the construction of the screen.

Referring now more particularly to the drawings, the numeral 10 generally designates a substantially semi-cylindrical trough, the upper edges of which are provided with inturned flanges or shoulders 11. A semi-cylindrical top 12 is provided for the trough which is hinged to the shoulders 11 at points spaced inwardly from the edges of the trough as at 13 and which is formed in two sections joining at their top as at 14, which may be separated and swung down at opposite sides of the tank to permit access to the screening apparatus hereinafter to be described. End heads 15 are provided closing the ends of the trough and of the semi-cylindrical cover 12 thereof.

The screening apparatus comprises end castings 16 each including a roller track 17 having associated therewith a gear 18 formed at one edge of the track. Projecting inwardly from the roller track is a cylindrical flange 19 the periphery of which is notched at spaced intervals as indicated at 20 to provide seats for longitudinally-extending, reinforcing and spacing ribs 21 preferably in T form and consisting either of a solid beam or an assembly of beams.

Projecting inwardly from the roller track 17 is a flange 22 forming a splash guard. Journaled in the end heads 15 are shafts 23, 23—a upon which are mounted combined roller and gear elements 24 for co-action with roller track 17 and their associated gears 18. These shafts are disposed adjacent the bottom

of the troughs and the elements 24 serve both to support the screen frame and as a driving means therefor, shaft 23 being projected at one end of the trough and associated with a 5 drive generally designated at 25.

Segmental screens 26 have their ends supported by the flanges 19 and their side edges supported by the ribs 21 being bolted or otherwise secured at these points. Each segmental 10 screen comprises an outer brass backing wire 27 against the inner face of which is disposed a finer screen of Monel metal 28. Against the inner surface of the Monel metal screen a twilled Monel metal cloth 29 of a desired mesh is disposed.

Supported by the end walls 15 and extending through one thereof is an open-topped, substantially V-shaped trough 30 which is disposed adjacent the top of the casing and 20 within the confines of the screen, the bottom of this trough being free from perforations within the casing but exteriorly of the casing being provided with a discharge canal 31. The outer end of this section of the trough is 25 formed with an outboard bearing 32 for a shaft 33 the opposite end of which is journaled in the remote end head of the casing. This shaft is driven from an extension of one of shafts 23 and within the casing is equipped 30 with a worm 35 for shifting material deposited in the trough longitudinally to the discharge canal 31 and to the exposed end of the trough from which it may be removed. The casing above the trough and exteriorly to the 35 screen has extending longitudinally thereof a spray pipe 36 for directing a spray against that portion of the screen which is passing over the trough to drive adhering matter therefrom into the trough. If hot water or 40 steam is employed a sterilization results as set forth in my prior patent hereinbefore noted.

Likewise extending longitudinally of the casing and supported at its ends therefrom 45 is an inlet or distributing pipe 37 the opposite ends of which are open and adapted for communication with feed pipes 38. Distributing pipe 37 is eccentrically disposed with relation to the screen and at the approximate 50 level of the axis thereof and has extending therefrom a plurality of radially directed pipes 39 the end portions of which are arranged in close proximity to the adjacent portions of the screen.

55 Clamped to the distributing pipe 37, as at 40, are substantially semi-circular baffles or auxiliary splash guards 41. These baffles are disposed immediately inwardly of annular flanges 22 and effectually cut off any splash 60 which might occur in the lower half of the casing, thus eliminating a tendency of dirty liquids within the screen to mingle with those lying exteriorly thereof.

In operation of the strainer, assuming the 65 apparatus to be driven, the fluid to be strained

is admitted simultaneously through pipes 38. This results in an equalization of pressures within the main distributing pipe 37 so that the discharge of the fluid is substantially uniform throughout the 70 length of the casing. The auxiliary distributing pipes 39 insure delivery of this fluid directly against the screen and at a time immediately after this screen has passed by the spray pipe to drive any material adhering 75 thereto into the trough 30. Foreign matter which cannot pass through the screen will be carried by the screen until it overlies the trough and will be removed therefrom by the spray pipe and deposited in the trough. Due 80 to the fact that this trough has no perforations within the straining zone, fine foreign matter which would otherwise have a tendency to collect in the straining zone is carried to the exterior of the machine where it 85 may be settled out before the fluid is again subjected to a straining action. Collected trash in the exposed end of the trough may be removed from time to time as this is found necessary. Due to the sectional formation of the casing cover and to the formation of the screens in removable sections, repairs may be readily made at any time when they become necessary.

The construction being capable of a considerable range of change and modification without in any manner departing from the spirit of my invention, I do not wish to be understood as limiting myself to the particular structure herein illustrated except as 90 hereinafter claimed.

I claim:

1. In straining apparatus, a rotating screen, a supply pipe extending into said screen and having outlets directed against the screen and means for simultaneously delivering fluid to be strained to opposite ends of said supply pipe, the outlets of said supply pipe comprising longitudinally distributed radially directed auxiliary pipes having their outlet 105 ends in close proximity to the screen, said pipes being disposed in a plurality of rows, the pipes of each row being staggered with relation to those of adjacent rows whereby the fluid is substantially uniformly distributed 110 along the length of the screens.

2. In a strainer and in combination, a tank, a solid-bottomed trough extending through said tank, a conveyor for moving material longitudinally from the trough, a substantially cylindrical screen surrounding the trough, means for rotating said screen, a supply pipe for delivering dirty liquid to the interior of the screen and baffle plates supported by said supply pipe for preventing 120 splashing of the dirty liquids through the ends of the screen.

3. A strainer and in combination, a rotatable screen including annular end elements each provided with an inwardly-directed 125

flange, a supply pipe extending through the screen for delivering fluid to the interior of the screen and baffles carried by said supply pipe and disposed inwardly of the flanges of the end members.

4. A strainer and in combination, a rotatable screen including annular end elements each provided with an inwardly-directed flange, a supply pipe extending through the screen for delivering fluid to the interior of the screen, baffles carried by said supply pipe and disposed inwardly of the flanges of the end members, and means for simultaneously delivering fluid to be strained to opposite ends of the supply pipe.

MARTIN E. CARTER.
